COLLAPSIBLE HANDLE HAND PUMP

Benjamin N. Ashton and Edmund D. Holland,
Kingston, N. Y., assignors to Electrol Incorporated,
Kingston, N. Y., a corporation of Delaware

Application December 29, 1942, Serial No. 470,480

1 Claim. (Cl. 74—525)

The present invention pertains to handles for manual operation of machines as for instance hydraulic pumps. It has for its object to provide a telescopic handle which can be easily retracted or extended by the operator. This permits reduction of the space occupied by the handle and enables the operator to adjust the leverage when desired.

With this object in view, the handle, according to the present invention, is provided with a base member to be attached to the member to be actuated, as for instance a plunger, and a grip to be seized by the operator and these elements are connected together by at least two tubes slidable in each other, one rigid with said grip and the other rigid with said base member.

According to a feature of the present invention, resilient means—such as a spring—are inserted between said base member and said grip, or between points on the tubes connecting said elements, to force the handle into its extended position.

According to a further feature, locking means are provided which will maintain the handle in its retracted position against the force of said spring. These locking means are adapted to be engaged by a slight rotary motion of the grip.

Further features may be gathered from the following detailed description of an embodiment of the present invention given by way of example and illustrated in the accompanying drawings, in which

Figure 1 is a longitudinal cross section of a handle according to the present invention;

Figure 2 is an elevational view of Figure 1, as viewed from the right hand side of the drawing;

Figure 3 is a side elevation of the same handle attached to the plunger of a hydraulic pump.

In Figure 1 reference numerals 1 and 2 designate the base member and the grip of the handle, respectively. Grip 2 is mounted on a plug 3 supported by a pin 4. From plug 3 two tubes 5 and 6, rigid with the same, extend toward member 1. A tube 7, bolted at 8 to member 1, extends toward grip 2 and slidably engages tube 5. At its free end, tube 7 carries a collar 9 slidably engaging tube 6.

A spring 10 is provided between projections 11 rigid with member 1 and retainers 12 and 12a rigid with tube 6.

A pin 13 rigid with tube 6 is carried in the annular socket 12, so that the end faces of the pin and the outer face of the socket slidably engages the inner surface of tube 7.

The provision of collar 9, pin 13 and sockets

12 and 12a insures proper spacing between tubes 6 and 7 at all times.

Another pin 14 rigid with tube 7 and traversing the projections of base member 1 and tube 6, is provided for the purpose of locking the handle in its retracted position.

Figure 2 shows a slot 15 provided in tube 6. Both figures show the handle in its locked position in which pin 14 is engaged in notched recess 17 of slot 15. A corresponding slot and notched recess are, of course, provided in the radially opposite side of tube 6 to accommodate the other end of pin 14, respectively. By a slight turn of grip 2, pin 14 can be disengaged, whereby tube 6 is set free to move axially, so that spring 10 can push the handle into its extended position. After the handle has been used in its extended position, the operator will push the grip home until pin 14 registers with recess 17. A slight turn of grip 2 in the opposite direction will then lock the handle against extension by the action of spring 10.

It is an advantageous feature of the locking arrangement that the turning of grip 2, necessary to disengage pin 14 from recess 17, subjects spring 10 to a torque, because this torque will assist during the return movement to bring pin 14 back into its locked position.

Handles according to the present invention may be considerably longer in their extended than in their retracted position. In such case, tube 6 will come out of contact with pin 14. The afore-mentioned torque of spring 10 may then cause tube 6 to turn back into the radial position which it occupies when the handle is locked. Upon returning the handle to the retracted position the operator will then have to turn grip 2 until pin 14 registers with slot 15 before the handle can be pushed home completely. This turn will reproduce the torque of spring 10 which assists placing the handle in its locked position. To facilitate the registering of pin 14 with slot 15 when the handle is retracted, it is advantageous to widen a portion of said slot near the end of tube 6 and also to shape the end of tube 6 so that the cam face will ride on the pin 14 and turn the tube 6 so that the slot is over the pin.

Figure 3 illustrates a handle according to the present invention pivotally attached at 18 and having a plunger 20 of a hydraulic pump pivotally affixed to it at 19, the considerable extension of which handles, according to the present invention are capable of making it possible to attach the base member directly to the member to

be actuated without unduly increasing the force necessary to operate the grip.

Handles of this type are particularly useful in connection with hydraulic equipment on aircraft where an economy of space and weight is imperative, and where an extension of the handle permits greater force to be applied by the pilot in pumping pressure into the hydraulic system. The retractable feature permits the pilot to keep the handle out of the way and yet easily extended to an operative position.

The foregoing description is not intended to limit the present invention which extends to all changes, modifications and equivalents comprehended within the scope of the appended claim.

What is claimed is:

Telescopic handle for hand actuated machines which comprises a grip to be seized by the operator, a base member to be directly connected to the element of said machine which is to be actuated and adapted to transmit to the same the forces exerted on said grip, said grip and said base member being connected together by three con-

centric tubes, the outer and inner of said tubes being rigid with said grip, the intermediary tube being rigid with said base member and adapted to engage slidably said outer tube, a collar interposed between the end of said intermediary tube and said inner tube, said collar being rigid with said intermediary tube and slidably engaging said inner tube, a pin carried in sockets formed by an outwardly recessed portion of said inner tube at a point distant from said base member, said pin and said sockets being rigid with said inner tube and slidably engaging said intermediary tube, a spring interposed between a portion of said base member and said sockets, a second pin rigid with said intermediary tube, two slots in said inner tube adapted to slidably receive said second mentioned pin, and two notched recessed portions in said slots adapted to receive said second-mentioned pin whenever the same registers with said recessed portions and said handle is turned.
